Primary Examiner — Karen E Eldridge Powers*(74) Attorney, Agent, or Firm* — Florek & Endres PLLC(57) **CLAIM**

I claim the ornamental design for a glove, as shown and described.

DESCRIPTION

FIG. 1 is a perspective view of the glove of the present invention.

FIG. 2 is a back elevation view of the glove of the present invention.

FIG. 3 is a front elevation view of the glove of the present invention.

FIG. 4 is a left side elevation view of the glove of the present invention.

FIG. 5 is a right side elevation view of the glove of the present invention.

FIG. 6 is a top elevation view of the glove of the present invention; and,

FIG. 7 is a bottom elevation view of the glove of the present invention.

The interior surfaces of the glove form no part of the claimed design.
